GRIPPER SHUTTLE LOOM

Erwin Pfarrwaller, Winterthur, Switzerland, assignor to Sulzer Frères, Société Anonyme, Winterthur, Switzerland, a corporation of Switzerland

Application January 10, 1951, Serial No. 205,236

Claims priority, application Switzerland August 20, 1947

10 Claims. (Cl. 139—125)

The present invention relates to a loom for weaving having gripper shuttles which, after having been picked through the shed by a picking mechanism, are received and brought to a standstill in a receiving mechanism and transferred therefrom to a conveyor on which they are returned to the picking mechanism, and more particularly to improved means for transferring the shuttles from the receiving station to the return conveyor.

The present application is a continuation-in-part of my co-pending application Serial No. 45,178, filed August 19, 1948, now Patent No. 2,538,798.

It is an object of the invention to provide means in connection with the shuttle receiving and brake mechanism of a gripper shuttle loom which assure positive removal of the shuttles from the receiving mechanism to clear the mechanism and the brakes therein for the shuttles to be received subsequently and which means assure orderly consecutive placement of the shuttles on a conveyor for returning the shuttles to the shuttle picking mechanism.

It is a further object of the invention to provide improved means for expelling gripper shuttles from a shuttle receiving and braking station to a return conveyor, which means assure orderly consecutive placement of the shuttles on the return conveyor at high speed, whereby the number of picks can be increased.

Another object of the invention is to provide, in a mechanism for transferring gripper shuttles from a receiving and braking station to a return conveyor, simple means for positively guiding the shuttles on their way from the receiving station to the conveyor, means for expelling the shuttles from said guide means, and means periodically blocking discharge of shuttles to the conveyor, whereby said blocking means are actuated by the shuttles when they are moved by said expelling means.

A further object of the invention resides in the provision of a shuttle transfer and expelling mechanism between a shuttle receiving and braking mechanism and a conveyor for returning the shuttles to a shuttle picking station in a loom for weaving, said transfer and expelling mechanism comprising an expeller for the shuttles and a blocking device for periodically blocking transfer of a shuttle to the conveyor, said blocking device being actuated by said expeller.

An object of the invention is to provide in a loom for weaving having gripper shuttles, a transfer and expelling mechanism interposed between a device for receiving and braking the shuttles after they have been picked through the shed by a picking mechanism, and a conveyor for returning the shuttles to the picking mechanism, said transfer and expelling device including a guideway for the shuttles, means for expelling the shuttles from the guideway, and a blocking member for periodically blocking passage of the shuttles through the guideway, whereby said blocking device is unblocked by said expeller through the agency of the shuttles in the guideway and is held in blocking position by said expelling means.

Further and other objects of the present invention will be hereinafter set forth in the accompanying specification and claims, and shown in the drawings which, by way of illustration, show what I now consider to be preferred embodiments of my invention.

In the drawings:

Fig. 1 illustrates diagrammatically a loom to which the devices according to the invention may be applied;

Fig. 2 is a diagrammatic part sectional side view of a mechanism according to the invention;

2

Figs. 3 to 6 diagrammatically show the expeller and blocking means of the device according to Fig. 2 in various operating positions;

Figs. 7 and 8 illustrate diagrammatically a modified expeller and blocking device according to the invention in two different operating positions;

Figs. 9 and 10 are diagrammatic sectional elevations of a further modification of an expeller and blocking system according to the invention in two different operating positions;

Fig. 11 is a plan view of the system shown in Figs. 9 and 10;

Figs. 12 and 13 are diagrammatic sectional elevations of yet another modification of a shuttle expeller and blocker according to the invention.

Like parts are designated by like numerals in all figures of the drawings.

Referring more particularly to Fig. 1 of the drawings, numeral 1 designates a casing containing a drive mechanism for driving or actuating the parts of the loom which must be operated for effecting weaving, such as a warp beam 2 unwinding the warp 3, heddle frames 13, and a cloth beam 5 for winding the fabric 4. The drive mechanism comprises a main shaft 6 for operating a shuttle picking mechanism 7 and a shuttle receiving mechanism 8. The picking mechanism 7 effects connection of a weft thread 10 with a shuttle 14 and picking the shuttle through the shed to the shuttle receiver 8 while the weft thread is unwound from a spool 11 which is situated outside of the shed. After having laid a weft thread in the shed, the thread is disconnected from the shuttle and the latter is returned to the picking mechanism 7 below the warp 3 by a return mechanism 9. The loom is started and stopped by manipulation of a lever 12 connected with a shaft 12' whose rotation effects actuation of a clutch 15 for connecting and disconnecting shaft 6 with a motor 16 and of a brake 17 for the shaft 6. Shaft 6 may be rotated by means of a hand wheel 18 if the shaft is disconnected from the motor 16. The individual parts set forth above are shown diagrammatically only as they do not form part of the present invention. Fig. 1 and its description are merely for the purpose of explaining the type of loom and general organization to which the subject matter of the present invention may be applied.

Figs. 2 to 6 illustrate that part of a shuttle receiving mechanism which is the subject matter of the present invention. After having passed through the shed, the shuttles arrive at a shuttle receiving device on a runway 103 and are brought to a standstill by means of a brake, for example as shown in my co-pending application Serial No. 45,178 now Patent No. 2,538,798. Thereupon the weft threads are disconnected from the shuttles and the latter are expelled through a guideway 149 and pushed onto a conveyor 146.

The guideways 149 (Figs. 2 to 8, 12 and 13) or 161 (Figs. 9 to 11) are formed by slots in the plates 160 whereby the ends of the shuttles are guided longitudinally by sheets 188 and 189 (Fig. 11) without slots. Sheet 189 has an opening 190 to permit passage of the shuttles from the shed to the runway 103. Several shuttles 151, 152, 153 may be in the guideway at a time. Fig. 2 shows the device in a position after shuttle 151 has been pushed from runway 103 into guideway 149 by means of push rods 98 and 99, the latter being seen in Fig. 11, in the manner disclosed in my application Serial No. 45,178.

Shuttle 153 has reached the discharge end of the guideway and is retained therat by a blocking member 170 having a face 171 on which the shuttle rests. Blocking member 170 is in the form of a lever swinging on pin 172 fixed on a stationary part of the loom. The lever is urged into blocking position by means of a spring 173. In the position of the mechanism shown in Fig. 2, an expeller member 113, which is fast on shaft 112, is in inoperative position. Shaft 112 is operatively connected by means of an arm 111 to a link system, 110, 109, 108 and the latter is pivoted at 86 to a lever 107 which is actuated by a cam 23 on shaft 6. Part 109 of the link system is a bellcrank lever swinging about stationary pin 105. Rotation of cam 23 effects oscillation or rocking of the expeller member 113. An abutment 174 is made fast on shaft 112 and has a face adapted to engage face 175

80

on member 170 for fixing the latter in blocking position when rocker or expeller member 113 is in inoperative position, whereby passage of shuttle 153 out of guideway 149 is blocked.

The mechanism operates as follows:

The expeller member 113 moves clockwise upon counter-clockwise rotation of cam 23 and engages shuttle 153 when the member has reached the position shown in Fig. 3. At this time, abutment 174 has left face 175 and unlocked member 170.

Upon further clockwise rotation of shaft 112, the expeller 113 swings blocking lever 170 through the agency of shuttle 153 out of the way of the latter, so that member 113 can continue its clockwise movement and push the shuttle down to conveyor 146 as seen in Figs. 4 and 5. In the position shown in Fig. 5, lever 170 has been returned to its blocking position by spring 173 and member 113 prevents falling down of shuttle 152 until member 113 is returned to its rest position, in which it is shown in Figs. 2 and 6. The pusher rods 98 and 99 can now push shuttle 150, which has in the meantime arrived on runway 103, into the guideway 149 and thereby advance shuttles 151 and 152 until the latter comes to rest on the face 171 of the blocking lever. The latter is locked in blocking position by the abutment 174. Shuttle 153 is carried away on conveyor 146 while being guided at the beginning by surface 177 of the blocking lever. The mechanism is now in the position shown in Fig. 2 and ready for the next cycle of operation in which shuttle 152 is expelled.

As seen in Fig. 2, the fulcrum 60 of lever 107 is yieldingly supported. It is mounted on a slide member 61 which is held in middle position by springs 210 and 211. The latter force plates 212 and 213, respectively, against bearing 214 which slidably supports member 61 whose ends are adjacent but not connected to plates 212, 213 when the fulcrum is in center position. Displacement of member 61 to the right is yieldingly resisted by spring 211 and the member may be displaced to the left from the position shown in Fig. 2 against the action of spring 210. A ball 64 resting on top of rod 65 is received in a recess 63 of member 61 when the latter is in middle position. Displacement of slide 61 from its center position forces ball 64 out of recess 63 and downward, whereby arm 43 fast on shaft 44 and supporting rod 65 is depressed and shaft 44 turned counter-clockwise. Shaft 44 actuates conventional means for stopping the loom, such as shown, for example, in my co-pending application Serial No. 714,022 of December 4, 1946, now Patent No. 2,546,833.

If a shuttle is jammed in guideway 149 and cannot be expelled, clockwise movement of expeller 113 cannot be completed and member 61 will move to the left. If lever 170 should not be able to return from the unblocking position in Fig. 4 to the blocking position, abutment 174 will hit the lower end of lever 170 and prevent counter-clockwise movement of expeller shaft 112, causing member 61 to move to the right. In both cases, ball 64 will be forced out of its recess 63 and will depress rod 65 and actuate the loom stop-motion shaft 44 causing a standstill of the drive of shaft 18 and preventing damage to the shuttle expelling mechanism.

The shuttle blocking member may be modified to have the configuration of a two-arm lever 178 as shown in Figs. 7 and 8. Lever 178 swings about a stationary fulcrum 179 and is urged by spring 180 resting against a stationary part of the loom into blocking position. The lower arm of lever 178 has a surface portion 171' on which shuttle 153 rests when the device is in the blocking position shown in Fig. 7. A surface portion 177' at the lower end of lever 178 serves as a guide for the shuttle 154 on conveyor 146.

The expeller member 181, which is fast on shaft 112, is provided with an abutment 182 engaging the end of the upper arm 183 of the blocking lever 178 and holding the latter in blocking position when the expeller is in rest position.

Fig. 8 shows the modified expeller mechanism in position for expelling shuttle 153. Shuttle 154 has been carried away on conveyor 146 and member 181 has been turned clockwise and its abutment 182 disengaged from arm 183. The member pushes shuttle 152 against shuttle 153 and the latter pushes the lower arm of blocking member 178 out of its way, permitting the expeller 181 to push shuttle 153 by means of shuttle 152 all the way

down and onto conveyor 146. Spring 180 can now swing the blocking lever back into blocking position for retaining shuttle 152 until shuttle 153 has been carried away. Counter-clockwise movement of expeller member 181 clears guideway 149 for advancement of shuttles 150 and 151.

Figs. 9 and 10 illustrate a further modification of a blocking device which is actuated by an expeller through the agency of the shuttles to be expelled from a guideway 161 which has the configuration of the letter S. A blocking pawl 184 swings on a stationary pin 186 and is urged to block the outlet of the guideway 161 by a spring 187. Movement of the pawl 184 by the spring 187 is limited and its blocking position defined by abutment of the pawl against a stationary part forming the guideway. No special provisions are made for locking the pawl 184 in blocking position. The conveyor 146 is in inclined position affording smooth transfer of the shuttles from the guideway to the conveyor. A guide rail 148 prevents 20 sliding of the shuttles laterally off the conveyor.

The guideways 149 or 161 may be cut out of a solid piece of material or they may be formed by a plurality of sheets 160 having slots of the desired configuration and being made fast on a longitudinal member 51 of the shuttle receiving device, as shown in Fig. 11. The expeller 185 (or 113 or 181) preferably has two arms which extend between the sheets 160. Only one shuttle 150, that on runway 103, has been shown in Fig. 11 so that the illustration of the guideway and of the expeller is not obscured.

Figs. 12 and 13 illustrate a further modification of the blocking lever and of the expeller device. The former, 191, swings about stationary pin 192. The expeller rod 193 swings about a pin 195 on the expeller arm 194, 35 which arm is fast on shaft 196. The expeller rod 193 slides in a guide hole 197. The upper part 198 of the blocking lever 191 has a projecting portion 199 abutting a collar 200 on rod 193 for locking the blocking lever 191 in blocking position when the expeller device 193, 40 194 is in rest position.

Shaft 196 is turned counter-clockwise for expelling shuttle 153 causing rod 193 to clear the projection 199 and permitting lever arm 191 to move to unblocking position. Hole 197 guides rod 193 for engagement of shuttle 153. This is shown in Fig. 13. Further downward movement of arm 194 causes downward movement of shuttle 153 and pushing of lever 191 out of the way of the shuttle, so that the latter can drop on conveyor 146. Arm 191 can move clockwise only until projection 199 50 abuts rod 193. Expeller rod 193 is guided in the hole 197 when the rod 193 is returned to its rest position. Surface 201 of the blocking lever 191 engages at the same time portion 200 of rod 193 causing movement of the blocking lever 191 into blocking position when surface 202 of the projecting portion 199 comes to rest against the cylindrical surface of collar 200 of the rod 193; the device is now once more in the position shown in Fig. 12, in which rods 98, 99 can advance the shuttles in guideway 149 for moving shuttle 152 to rest on surface 203 of the blocking lever 191.

While I believe the above described embodiments of my invention to be preferred embodiments, I wish it to be understood that I do not desire to be limited to the exact details of design and construction shown and described, for obvious modifications will occur to a person skilled in the art.

I claim:

1. In a gripper shuttle loom of the type having shuttle picking means, shuttle receiving and braking means, and shuttle return means for returning the shuttles from said receiving and braking means to said picking means; passage means for the shuttles interposed between said receiving and braking means and said return means, shuttle expelling means for expelling the shuttles from said passage means, and a blocking lever having an end portion adapted to block discharge of shuttles from said passage means and said end portion being adapted to be engaged by said expelling means for locking said lever in its blocking position.

2. In a loom for weaving of the type having gripper shuttles, shuttle picking means, shuttle receiving and braking means, and shuttle return means for returning the shuttles from said receiving and braking means to said picking means; a guideway for the shuttles interposed between said receiving and braking means and said return

means, shuttle expelling means for expelling the shuttles from said guideway, and blocking means adapted to be actuated by said expelling means and controlling passage of the shuttles from said guideway to said return means and having a guide surface for guiding the shuttles when they are on said return means.

3. In a loom for weaving of the type having gripper shuttles, shuttle picking means, shuttle receiving and braking means, and shuttle return means for returning the shuttles from said receiving and braking means to said picking means; a guideway for the shuttles interposed between said receiving and braking means and said return means, shuttle expelling means adapted to extend periodically into said guideway for advancing the shuttles therein, and blocking means adapted to be actuated by the shuttles upon advancement thereof in said guideway by said expelling means for controlling passage of the shuttles from said guideway to said return means.

4. In a loom for weaving of the type having gripper shuttles, shuttle picking means, shuttle receiving and braking means, and shuttle return means for returning the shuttles from said receiving and braking means to said picking means; a guideway for the shuttles interposed between said receiving and braking means and said return means, shuttle expelling means for expelling the shuttles from said guideway, and blocking means adapted to be actuated by said expelling means by the agency of said shuttles for controlling passage of the shuttles from said guideway to said return means.

5. In a loom for weaving of the type having gripper shuttles, shuttle picking means, shuttle receiving and braking means, and shuttle return means for returning the shuttles from said receiving and braking means to said picking means; a guideway for the shuttles interposed between said receiving and braking means and said return means, shuttle expelling means for expelling the shuttles from said guideway, blocking means adapted to be actuated by said expelling means and controlling passage of the shuttles from said guideway to said return means, and resilient means connected with said blocking means and a stationary part of the loom for urging said blocking means into blocking position.

6. In a gripper shuttle loom of the type having shuttle picking means, shuttle receiving and braking means, and shuttle return means for returning the shuttles from said receiving and braking means to said picking means; passage means for the shuttles interposed between said receiving and braking means and said return means, shuttle expelling means including a rotatable shaft and an expeller element fast on said shaft for expelling the shuttles from said passage means, a blocking lever having an end portion adapted to block discharge of shuttles from said passage means, and an abutment fast on said shaft and adapted to engage said end portion for locking said lever in its blocking position.

7. In a gripper shuttle loom of the type having shuttle picking means, shuttle receiving and braking means, and shuttle return means for returning the shuttles from said receiving and braking means to said picking means; passage means for the shuttles interposed between said receiving and braking means and said return means, shuttle expelling means for expelling the shuttles from

said passage means, and a blocking lever having an end portion adapted to block discharge of shuttles from said passage means and to be engaged by said expelling means for locking said lever in its blocking position; said passage means including a horizontal straight inlet portion, a curved portion having the configuration of a quarter circle, and a vertical straight outlet portion; said blocking lever being substantially straight and vertical.

8. In a gripper shuttle loom of the type having shuttle picking means, shuttle receiving and braking means, and shuttle return means for returning the shuttles from said receiving and braking means to said picking means; passage means for the shuttles interposed between said receiving and braking means and said return means, shuttle expelling means comprising a bifurcated expeller element whose prongs engage the shuttles for expelling the shuttles from said passage means, and a blocking lever having an end portion adapted to block discharge of shuttles from said passage means and to be engaged by said expelling means for locking said lever in its blocking position, said blocking lever extending between the prongs of said expeller element.

9. In a gripper shuttle loom of the type having shuttle picking means, shuttle receiving and braking means, and shuttle return means for returning the shuttles from said receiving and braking means to said picking means; passage means for the shuttles interposed between said receiving and braking means and said return means, shuttle expelling means including a bifurcated expeller element whose prongs engage the shuttles for expelling the shuttles from said passage means, and a blocking lever having an end portion adapted to block discharge of shuttles from said passage means and to be engaged by said expelling means for locking said lever in its blocking position, said passage means comprising a plurality of vertical flat plate members having slots forming a passage for the shuttles, the prongs of said expeller element extending between said plate members.

10. In a gripper shuttle loom of the type having shuttle picking means, shuttle receiving and braking means, and shuttle return means for returning the shuttles from said receiving and braking means to said picking means; passage means for the shuttles interposed between said receiving and braking means and said return means, shuttle expelling means including a bifurcated expeller element whose prongs have flat surface portions engaging the shuttles for expelling the shuttles from said passage means, and a blocking lever having an end portion adapted to block discharge of shuttles from said passage means and to be engaged by said expelling means for locking said lever in its blocking position, said shuttles having a rectangular cross sectional configuration, the corners of the rectangle being bevelled to form flat surfaces for flat engagement by the flat surfaces of said prongs.
